UNITED STATES PATENT OFFICE.

ALBERT H. NELLER, OF FAIRFIELD, IOWA, ASSIGNOR TO LOUDEN MACHINERY COMPANY,
OF FAIRFIELD, IOWA, A CORPORATION OF IOWA.

ELEVATED CARRIER.

No. 873,165.

Specification of Letters Patent.

Patented Dec. 10, 1907.

Application filed July 23, 1906. Serial No. 327,354.

To all whom it may concern:

Be it known that I, ALBERT H. NELLER, a citizen of the United States, residing at Fairfield, in the county of Jefferson and State of Iowa, have invented a new and useful Improvement in Elevated Carriers, of which the following is a specification.

My invention relates to elevated carriers such as are generally used for carrying feed, litter and other products, and it consists principally of an improved form of truck whereby the track wheels will be securely held in place and yet be free to run on a curved track, or on curved track sections used to connect together two sections of track running at an angle, so as to form a continuous track-way. Also, of other features which will be set forth in the specification and specifically pointed out in the claims.

In the accompanying drawings forming a part of this specification, Figure 1 is a front perspective of a carrier embodying my invention. Fig. 2 is a rear perspective of one end of the carrier. Fig. 3 is a vertical cross section on line 3—3 of Fig. 2. Fig. 4 is a plan or top section of the track upon which the carrier is designed to run. Fig. 5 is a horizontal section on the line 5—5 of Fig. 2.

Referring to the drawings, A represents an overhead track which is shown as a suspended wire or cable but may be of other suitable construction.

B is a carrier frame which is essentially a horizontally disposed bar preferably made of angle iron and having downwardly turned ends B' to which the necessary attachments may be connected.

C represents upwardly extending brackets which are secured at their lower ends to the carrier frame and are extended up and over the track.

Interposed between the main brackets and the frame are supplemental brackets D extending up under the track. A short distance above the frame the main brackets are bent out laterally from the vertical line of their lower ends and are then further extended and their upper ends are bent inwardly substantially at right angles to their bodies so as to be substantially in a vertical line above the bar B. The supplemental brackets are extended up a short distance and their upper ends are also bent inwardly at substantially right angles to their bodies

so as to stand in the same vertical line as the upper ends of the main brackets.

Holes are made in the upper ends of the brackets C and D in vertical line with each other and pivots are inserted therein. In the lower brackets threaded pins E having nuts F and G are preferably used. The nuts F are placed above and the nuts G below the ends of the brackets and are drawn up securely so as to hold the pins firmly in place, and leave their upper ends projecting sufficiently to form a pivot. The holes in the upper ends of the brackets C are preferably threaded and set screws H having points suitable for pivots are inserted therein. Lock nuts I are also preferably used to hold the set screws in place and to permit the adjusting of their pivot points in proper position. There being two sets of these brackets and their attachments, a description of one will hereafter be considered a description of the other.

J represents a housing which is adapted to carry a track wheel K, and also to turn on the pivots aforesaid. This housing is preferably made of sheet metal and has its upper end bent U shaped. A bolt L is placed in the central part of the housing as shown, and a wheel K is mounted upon said bolt. The lower end of the housing is bent inwardly substantially at right angles to its body so as to correspond with the upper ends of the bracket D and a hole is made therein to fit over and turn upon the pivot pin, E. In the upper end of the housing a hole is also made to receive the pivot in the brackets C. A block N is preferably inserted in the upper end of the housing immediately below the hole therein.

To place the housing in position the set screw H is loosened, the lower end of the housing is set on the pivot E, the set screw is turned down so its point will enter the hole in the upper end of the housing and come in contact with the block N, and the lock nut I is turned down to hold the set screw in place. It will be seen that the housing carrying the wheel K will be free to turn at an angle to the bracket C in one or both directions as shown by cross section in Fig. 5. The object of this construction is to enable the carrier to run freely on a curved or crooked track, as well as to be transferred from one track to another running at an angle thereto by means of a

bent or curved section joining the two tracks together. An illustration of the latter is shown in Fig. 4, in which A' represents two suspended wire tracks crossing each other at

5 an angle and M a curved section joining the two tracks together so as to form a continuous way from one track to the other for the carrier to run upon.

The section M is preferably made of a 10 round rod or pipe. Its ends are cut away on the under side so it will fit over and partially or wholly surround the wires forming the tracks. If a pipe is used the wires may be passed into the ends and out of an opening on 15 the under side of the pipe where it curves away from the track. If a solid rod is used, grooves may be cut on the under side along each end so as to fit properly over the wires, and the lips of the groove at each end may be 20 hammered or bent in under to prevent them from springing off the track wires. It is also preferable that the ends of the section be beveled and reduced to substantially the same size as the wires, so that the wheels will 25 run smoothly on and off the curved section. Furthermore, to adapt the wheels to run properly on the wires and on the curved section when of larger diameter than the wires, I form two grooves in the wheels. The 30 larger groove, the size of which is shown by the dotted line O is intended to fit the curved section M, while the smaller groove, the size of which is shown by the dotted lines P, is formed in the center of the larger groove, and 35 is designed to fit the wire to which the section M is connected. By this means the wheels will always run freely and evenly on the wire and on the curved section connecting them together no matter how much the 40 carrier may be swung sidewise in passing over the curved section from one track to the other. Neither will it be necessary to kink the track wires nor to use extraneous clamping device to hold the section M in place.

45 In order that the brackets C may be more securely braced to the carrier frame, I have split their lower ends and spread them apart so as to form two diverging braces Q and R which are bolted at separate points to the bar 50 B. The supplemental brackets D are also widened at their lower ends so as to take in both of these bolts, and will therefore be held more securely in place. To further strengthen the frame and brackets the braces 55 R may be extended down and bolted to the depending ends of the bar B.

What I claim is:—

1. In elevated carriers, overhead tracks set at an angle to each other, a curved section joining said tracks together so as to form a continuous way, a carrier frame, a pair of upwardly extending brackets secured at their lower ends to said frame, one member of 60 which extends up under and the other up by 65 and over the track, housings pivoted between

said brackets so as to turn at an angle thereto, and wheels adapted to run on the track and on the curved section thereof mounted in said housings.

2. In elevated carriers, overhead tracks 70 set at an angle to each other, a curved section joining said tracks together so as to form a continuous way, a carrier frame, a pair of upwardly extending brackets secured at their lower ends to said frame, one member of 75 which extends up under and the other up by and over the track, housings pivoted between said brackets so as to turn at an angle thereto in both directions, and wheels adapted to run on the track and on the curved section there- 80 of mounted in said housings.

3. In a device of the character described, a carrier frame, a pair of main brackets secured at their lower ends to the frame, and having 85 their upper ends bent at an angle to their bodies on the side next to the frame, a pair of supplemental brackets secured at their lower ends between the main brackets and the frame, and their upper ends bent at an angle so as to be directly below the upper ends of 90 the main brackets, pivots mounted in the upper ends of the brackets, a pair of housings mounted on said pivots, and wheels adapted to run on the tracks and on the curved section joining the tracks together, mounted in 95 said housings.

4. In a device of the character described, having brackets and housings constructed and arranged substantially as set forth, the lower ends of the main brackets being 100 divided and diverged, and secured to the carrier frame at two separate points so as to brace the brackets thereon.

5. In a device of the character described, having brackets and housings constructed 105 and arranged substantially as set forth, the lower ends of the main brackets being divided and diverged, and secured to the carrier frame at two separate points so as to brace the brackets thereon, and one of the 110 divided ends being extended down and secured to a depending part of the carrier frame.

6. In a device of the character described, having brackets constructed and arranged substantially as set forth, a threaded pivot pin secured to the upper ends of the supplemental brackets by nuts on each side of said ends, a set screw having a downward pivot point mounted in the upper ends of the main 115 brackets, housings having their lower ends bent at an angle to their bodies and mounted on said pivot pins, and an opening in their upper ends for the admission of the pivot points of the set screws, said housings carrying 120 wheels adapted to run on the tracks and on the curved section joining them together.

7. In a device of the character described, having brackets constructed and arranged substantially as set forth, a threaded pivot 130

- pin secured to the upper ends of the supplemental brackets by nuts on each side of said ends, a set screw having a downward pivot point mounted in the upper ends of the main brackets, housings having their lower ends bent at an angle to their bodies and mounted on said pivot pins, openings in their upper ends, blocks secured therein below said openings, the pivot points of the set screws, being placed in said openings so as to come in contact with the blocks and lock nuts to hold the set screws in position, said housings carrying wheels adapted to run on the tracks and on the curved section joining them together.
8. In elevated carriers two separate overhead track wires crossing each other at an angle, and a curved section, round shaped in cross-section, having its ends fitted to approximately encircle the wires, and to connect thereto, so as to form a runway for a carrier from one wire to the other.
9. In elevated carriers, two separate overhead track wires crossing each other at an angle, and a curved tubular section having its ends fitted to approximately encircle the wires, and to connect thereto, so as to form a runway for a carrier from one wire to the other.
10. In elevated carriers, two separate overhead track wires crossing each other at an angle, and a curved section, round shaped in cross-section, having its ends fitted to approximately encircle the wires, and to connect thereto, so as to form a runway for a carrier from one wire to the other.
11. In a device of the character described, two round wire tracks placed at an angle to and crossing each other and a round shaped section of larger diameter curved and fitted to join the cross tracks together and form a continuous track-way, and a carrier having a wheel with a groove to fit and run upon the larger diameter of the curved section, and a smaller groove in the center of the larger groove to fit and run upon the smaller diameter of the track wires.
12. In elevated carriers, a frame, a pair of upwardly extending brackets secured to one side of the frame the upper end of one member of each pair being extended above and in vertical line with the upper end of the other member, housings pivotally mounted between the upper ends of said brackets so as to be free to turn at an angle thereto, and wheels adapted to run upon an overhead track mounted in said housings.

ALBERT H. NELLER.
